DESIGN FOR A CONTAINER FOR TOILET ARTICLES

Herbert H. Harris, New York, N. Y.

Application September 28, 1939, Serial No. 87,408

Term of patent 7 years

To all whom it may concern:

Be it known that I, Herbert H. Harris, a citizen of the United States and resident of New York, in the county and State of New York, have invented a new, original, and ornamental Design for a Container for Toilet Articles, of which the following is a specification, reference being had to the accompanying drawing, forming part thereof.

In the drawing:

Fig. 1 is a side view of a container for toilet articles showing my new design.

Fig. 2 is a top plan view thereof.

Fig. 3 is a bottom plan view of the same.

I claim:

The ornamental design for a container for toilet articles, substantially as shown.

HERBERT H. HARRIS.
